SASH HINGING HARDWARE

Filed March 30, 1943

UNITED STATES PATENT OFFICE

2,383,395

SASH HINGING HARDWARE

Peter H. Kuyper, Pella, Iowa, assignor to Roll-Screen Company, Pella, Iowa, a corporation of Iowa

Application March 30, 1943, Serial No. 481,118

1 Claim. (Cl. 16—166)

My present invention relates to sash hinging hardware particularly adapted for a swinging sash in a window frame, such as the kind shown in my copending application, Serial No. 463,338, filed October 26, 1942.

An object of my invention is to provide sash hinging hardware which is simple to manufacture and install and which involves a minimum of parts and expense.

Another object is to provide sash hinging hardware which is formed so that it has inherent means for holding the sash in various adjusted positions.

Still a further object is to provide sash hinging hardware including shoes and guides, the shoes being supported by arms which are so formed or bent as to cause the shoes to frictionally engage the guides and thereby hold the sash in various adjusted positions.

More particularly, it is my object to provide sash hinging hardware including arms secured to opposite edges of the sash and having shoes and links connected therewith, opposite frame members of a window frame having guides to receive the shoes, the arms being bent so that the shoes initially assume a position spaced farther apart than the distance between the guides, so that when the sash is installed the shoes frictionally engage the guides.

With these and other objects in view, my invention consists in the construction, arrangement and combination of the various parts of my device whereby the objects contemplated are attained, as hereinafter more fully set forth, pointed out in my claim and illustrated in the accompanying drawing, wherein:

Figure 1 is an inside elevation of a window with the sash hinging hardware embodying my present invention applied thereto, certain parts being broken away and others shown in section to illustrate the hardware in relation to the window frame and the sash;

Figure 2 is a vertical sectional view on the line 2—2 of Figure 1, this figure being on an enlarged scale and parts being broken out to conserve space on the drawing;

Figure 3 is a similar enlarged sectional view on the line 3—3 of Figure 1, and

Figure 4 is an enlarged horizontal sectional view on the line 4—4 of Figure 1.

On the accompanying drawing, the window frame illustrated has a sill 10, a pair of side jambs 12 and a head jamb 14. This frame is designed to be mounted directly in a wall opening, and to have a pane of glass 16 glazed directly therein. A sash,

comprising a pane of glass 18, lower and upper rails 20 and 22 and a pair of stiles 24, is mounted in an opening of the window frame for movement to closed or open position relative to such opening. Such an arrangement makes a relatively simple window structure for factories and low cost homes, as brought out in my copending application hereinbefore referred to.

My present invention has to do with the hardware for supporting the sash in the window opening for opening and closing movement. The top of the window opening is defined by a mullion 26 and the sill 10 and this mullion are provided with weather-seal flanges 28 and 30, respectively, which 10 interfit with the rabbets 34 and 32 of the sash when it is closed as shown in Figure 2. The side jambs 12 are likewise provided with flanges 36 15 with which rabbets 38 interfit in the closed position, with the hardware interposed therebetween, 20 as will hereinafter appear.

My sash hinging hardware comprises in general four elements, to-wit, a channel-shaped guide 40, a shoe 42 to slide therein, an arm 44 for attachment to the sash and a link 46. Two of these 25 units are provided, one for each side of the sash. The channel-shaped guide 40 is secured as by a series of spaced screws 48 to the side jambs 12 adjacent the flanges 36. The shoes 42 are likewise channel-shaped and fit in the guides 40, as shown

30 in Figure 4. The shoes in turn are pivoted as at 50 to the upper ends of the arms 44. The arms themselves are secured as by screws 52 to the stiles 24 of the sash. They are secured in a sub-rabbet 54 of the stiles, which sub-rabbets thereby 35 provide the necessary room for receiving the arms and also the links 46. The arms and links are angle-shaped in cross section so as to fit into the rabbets and the sub-rabbets 38 and 54, as shown in Figure 4; the links 46 so fitting of course only 40 when the sash is closed. This arrangement provides a snug interfitting between the sash, the window frame and the hardware without interfering with the operation of the hardware when opening or closing the window.

45 The links 46 are pivoted at their upper ends as shown at 56 to the arms 44. At their lower ends, wood screws 58 extend through the links and into the side jambs 12 for pivoting the links to the window frame. Accordingly, as the lower edge of 50 the sash is pushed toward the left from its position in Figure 2, it will cause the links 46 to swing out as to the position of Figure 3 and at the same time the shoes 42 will slide downwardly in the channel-shaped guides 40.

55 To hold the window in any adjusted position, it

is desirable to have the shoes 42 frictionally engage in the guides 40. This is accomplished by bending the arms 44 outwardly at the point indicated as 60 in Figure 3, with the initial bending of such extent that when the sash is installed the shoes 42 will be frictionally engaged with the webs of the channels 40. This is done by simply having the bends 60 of such an angle that the shoes are initially spaced farther apart than the distance between the webs of the channels. In Figure 1, for instance, I have shown the left side of the window frame broken away and the arm 44 in its initial position such that the shoe 42 is farther from the center of the window than the guide 40. After installation, the arms are under tension because of being forced back to the position shown at the right side of Figure 1. Thus, I provide a simple means to produce the necessary friction for holding the window at any desired position of adjustment without complicating the hardware with additional coil springs or the like. At the same time, the hardware is designed so as to minimize strains on the sash itself, due to the shoes 42 and the links 46 being pivoted to the arms 44 instead of directly to the sash. This arrangement also insures proper spacing of the pivots 50 and 56.

Some changes may be made in the construction and arrangement of the parts of my device without departing from the real spirit and purpose of my invention, and it is my intention to

cover by my claim any modified forms of structure or use or mechanical equivalents which may be reasonably included within its scope without sacrificing any of the advantages thereof.

5 I claim as my invention:

Sash hinging hardware comprising guides adapted to be attached longitudinally along opposite sides of a window frame, arms adapted to be attached to the adjacent edges of the sash, said arms being angle-shaped in cross-section, shoes pivoted to said arms at one end and links pivoted to said arms at the other end, said links being angle-shaped in cross-section, said shoes sliding along said guides and the other end of said links adapted to be pivoted to said sides of said window frame, the end portions of said arms to which said shoes are pivoted being bent away from each other so that the shoes are initially farther apart before installation of the sash in the window frame than said guides after they are installed on said window frame to cause the shoes to frictionally engage said guides during their sliding movement therewith, each side of said sash having a pair of rabbets, each of said arms having its two flanges located in said pair of rabbets and each of said links, when the sash is closed, forming an extension of its respective arm and having its two flanges also located in said pair of rabbets.
